UNITED STATES PATENT OFFICE

2,541,596

ROOF-FRAMING CALCULATOR

Gilbert E. Martin and Warren E. Lopez, New Orleans, La.; said Martin assignor to said Lopez

Application September 9, 1949, Serial No. 114,854

1 Claim. (Cl. 235—88)

1

Our invention relates to improvements in disc calculators, and more particularly to a more efficient and easily-used calculator for quickly and accurately ascertaining the correct angles for the various cuts required to be made in the structural components of roofs with the aid of a framing square, the primary object of the invention being to provide a device of this kind which furnishes all of the information as to the various cuts to be made in the components of a roof of known pitch from a single setting of the device.

Another important object of the invention is the provision of a device of the above-indicated character which is capable of a plurality of such single settings corresponding to roofs of different pitches, and involves means for locking the same in any of such settings.

A further important object of the invention is the provision of a device of the character indicated above which is of simple and mechanically-adequate construction, so as to be capable of being made in a serviceable and attractive form at relatively low cost.

Other important objects and advantageous features of our invention will be apparent from the following description and accompanying drawings, wherein, merely for purposes of illustration herein, a specific embodiment of the invention is set forth in detail.

In the drawings:

Figure 1 is a top plan view, showing a setting of the device;

Figure 2 is a transverse vertical section taken on the line 2—2 of Figure 1;

Figure 3 is an enlarged horizontal section taken on the line 3—3 of Figure 2 and showing the markings on the rotary disc;

Figure 4 is an enlarged perspective view of the pivot.

Referring in detail to the drawings, the numeral 5 designates a flat circular base of appropriate material formed with a peripheral groove 6 defining a shoulder 7 at its lower side. Seated in the groove 6 upon the shoulder 7 is the depending rim flange 8 of the circular top plate 9, the top plate 9 being thereby spaced upwardly from the base 5 and secured in place by screws or the like 10 traversing the flange 8 and entering the base. The top plate 9 is opaque and has openings, hereinafter described, which are covered by a transparent plate 11 secured to the under side of the top plate.

A pivot element, generally designated 12, comprises, as clearly shown in Figure 4, upper and lower axially-aligned cylindrical portions 13 and

2

14, respectively, projecting centrally from the upper and lower sides, respectively, of the square plate 15. The lower end of the lower portion 14 is rounded, as indicated at 16, to seat rotatably in a concavity 17 formed in the top of the base 5, as shown in Figure 2. The upper end of the upper portion 13 is provided with an axial, threaded bore 18. The pivot element 12 is so proportioned that with the rounded lower end of the portion 14 seated in the base concavity 17, the square 15 is positioned on a level midway between the transparent plate 11 and the base 5, with the upper portion 13 projecting upwardly through a journal hole 19 provided in the top plate 9. Upper and lower washers 20 and 21, respectively larger than the square plate 15, are circumscribed on the pivot element portions 13 and 14 and substantially take up the spaces between the upper and lower sides of the square plate 15 and the lower surface of the transparent plate 11 and the upper surface of the base 5, respectively, whereby the pivot element 12 is restricted to a small amount of vertical movement. A knob 22 having a cavity 23 in its under side receiving the upper end of the upper pivot portion 13 is vertically traversed by a screw 24 threaded into the bore 18 which holds the knob fixedly on the pivot element with the under side of the knob close to the upper surface of the top plate 9.

30 The rotary disc 25 is a plane flat circular disc whose peripheral edge 26 is squared and is concentrically spaced from the rim flange 8 of the top plate 9. The disc 25 is of the same thickness at its center as the pivot element plate 15 so as to turn snugly between the washers 20 and 21 and is formed with a square hole 27 conformably receiving the square plate 15, whereby the disc 25 is rotatable with the pivot element 12 as the knob 22 is manually rotated to selectively position or 40 set the disc 25. It will be noted that the hole 27 is of the same polygonal shape as said plate 15. For holding the disc 25 in a desired setting, a set screw 28 is threaded horizontally through the rim flange 8 to bear against the peripheral edge 26 and may be loosened or tightened by manually turning its head 29 which is positioned radially outwardly from the rim flange 8.

45 The top plate 9, as shown in Figure 1, is formed therethrough with a plurality of openings exposing the upper surface of the disc 25 through the transparent plate or sheet 11, the openings being arranged in predetermined groups and positions relative to each other and to markings on the disc 25.

50 55 Reading clockwise from the upper left portion

of three segmental roof pitch-selecting openings 30, 31 and 32 which are arranged to expose corresponding arcs of related indicia 30', 31' and 32', respectively, provided on the disc 25. The outer arc 30' designates the selected roof pitch, while the intermediate arc 31' designates the proper length of the selected gable cripples for 16 inches on center, while the inner arc 32' designates the proper length of the gable cripples for 24 inches on center. The registration of the outer pitch-selecting opening 30 with the selected one of the indicia of the outer arc 30' sets the disc 25 for all of the other information supplied by the device. When so set, the set screw 28 is tightened to hold the disc 25 in position so that correct reading of the device in the set position is assured.

With the hole 30 registered with the selected indicia of the arc 30', another outer group consisting of radially-aligned holes 33, 34, 35 and 36 expose related ones of the indicia of arcs 33', 34', 35' and 36' on the disc 25 giving the lengths of common rafters. Also aligned with this group of openings is an inner opening 37 exposing an arc 37' on the disc 25 showing the correct collar brace cut; and another inner opening 38 exposing an arc 38' on the disc 25 showing the correct length of jacks for twenty-four inches off center.

Another outer group consisting of radially-aligned holes 39, 40, 41 and 42 expose individual indicia of arcs 39', 40', 41' and 42', respectively, on the disc 25, showing correct hip lengths. An inner opening 43 aligned with this group exposes one of the indicia on an inner arc 43' to show the correct hip cut, and another inner arc 44' to show the correct jack length for sixteen inches on center.

The three groups described above are spaced at about 120° apart. Further inner openings, spaced equidistantly between the three outer groups described above, include, in clockwise order, the inner openings 45, 46 and 47, exposing indicia at equally-circumferentially-spaced points on an inner circle 48 on the disc 25, the opening 45 showing the correct cut for gable cripples, the opening 46 the correct cut for sheathing, and the opening 47 the correct cut for the jacks.

As herein disclosed, the device has ten roof pitch settings, the arc 30' on the disc 25 being composed of ten circumferentially-spaced triangles 49 having numerals 50, 51 and 52 designating lengths of the bases, altitudes and hypotenuses, respectively, of the triangles, the triangles ranging from a right triangle. In all instances the indicia of the outer and inner arcs are radially aligned in the various groups.

Common rafters

When the device is set, the information exposed by the pitch setting opening 30 is the plumb and level cut of the common rafter of 12 inches run, with the pitch determining the rise. The proper length for the common rafters is obtained from the numeral 53 alongside the openings 33 to 36, relating to different runs. The indicia exposed by the openings 33 to 36 give the lengths for the common rafters as indicated by the numerals 53. In determining the cut of a common rafter having a run other than those indicated by the numerals 53, the numeral 53 closest to the desired run is taken and one foot is either added or subtracted as many times as the desired run is greater or less than the given run. For example, the cut for a desired 13-foot

run can be obtained by laying off on the timber the given length for 12 feet and then extending the length one-times-one foot. In the case of a desired run of 19 feet, the solution would be to take the 20-foot run, subtract 1 foot of given run, and obtain 19 feet as the desired run. If the desired run should be 15 feet, ten feet of given run is taken and 5 feet is added thereto. The cuts for fractional lengths may be similarly obtained.

10

Hip rafters

Hip or valley rafters normally have a run of 16.97 inches to every foot of run on the common rafters, so that for practical purposes 17 inches 15 is used for the level cut just as a 12-inch cut is used for the common rafters. The side cuts for the hip rafters are found exposed in the opening 43, and the lengths in the openings 39 to 42. The plumb cut and the intermediate given lengths 20 are obtained as in the case of the common rafters.

Jack rafters

The plumb and level cuts for the jack rafters are obtained as in the case of the common rafters, but the side cuts of the jack rafters are obtained from the opening 47, the lengths of the jack rafters being determined by the number of feet on center at which they are spaced. The lengths given in the opening 44 are for the shortest jack. The length of the longest jack rafter may be obtained by subtracting the shortest jack rafter length from the related common rafter length. To get the length of the next to the shortest jack rafter, the length given in the opening 44 is added to the length of the shortest jack rafter.

Gable cripples

The openings 31 and 32 give the lengths for 40 the shortest cripples for the on-center arrangements indicated alongside these openings. If working from center, the longest cripple that will fit in the gable peak is measured and from this is subtracted the given length measuring from the 45 peak down, and the remainder is the length of the next shorter cripple. Working from the center of the cripples, that is, next to the longest cripple that is in place in the peak, all other cripples are measured from the peak of each cripple 50 after the second cripple, always subtracting the given length until the last cripple is reached. The top cut for the cripples which is obtained from the opening 45 can also be used for battens for the gable and for corner strips, and for any 55 vertical elements which intersect the roof in its rake.

Collar braces

The end cuts for collar braces are obtained 60 from the opening 31, but the length for the collar braces is not given, since this depends upon the height from the ceiling joist desired. The same cut can be used for weatherboard or anything running horizontal and intersecting the roof in its rake.

65

Sheathing

The cuts for sheathing are obtained through the opening 46 in the disc 25 which relates to placing sheathing around hips or in valleys.

70

We claim:

In a calculator, a base, a plate arranged in spaced parallel relation to and fixedly supported on said base, a circular disk positioned between said base and said plate, said disk being formed 75 with a polygonal center hole, a pivot element ex-

tending through the hole in the disk, said pivot element having one end journaled on said base and its other end extending through an opening formed in said plate and projecting outwardly beyond said plate, said pivot element having a polygonal portion spaced from its ends and positioned in said polygonal center hole whereby said pivot element and said disk are connected for rotation together, spacing means positioned on said pivot element at opposite sides of said polygonal portion and spacing said polygonal portion and said disk from said base and from said plate, and a disk rotating knob larger in diameter than and fixed on the said other end of the pivot element and bearing against the outer side of said plate.
